John M. He
Attorney,

H. W. HAYDEN, OF WATERBURY, CONN.

Letters Patent for a design No. 69, dated June 25, 1861.

SPECIFICATION.

TO ALL WHOM IT MAY CONCERN:

Be it known, that I, H. W. HAYDEN, of Waterbury, in the county of New Haven and State of Connecticut, have invented or produced a new and original design for a Mat for Daguerreotype, Ambrotype, and Photograph Cases; and I do hereby declare that the following is a full, clear, and exact description of the same, reference being had to the annexed drawing making a part of this specification.

The said drawing represents a front or face view of a mat embellished with my design.

The design is a national one, consisting of an eagle, two flags, a cannon, muskets, a scroll containing the words "E Pluribus Unum," and a row of stars placed around the opening in the mat.

The above named parts are disposed as follows: Around the elliptical opening A in the mat are placed the stars α , and at the top of the opening A there is the eagle B with extended wings.

At each side of the opening A, just below the eagle, there is an American flag B'. These flags extend down to about the centre of opening A, and a series of musket barrels C, with fixed bayonets, project from the opening at each side, immediately below the flags. Below the muskets there is a scroll D, containing the words "E Pluribus Unum," and below the scroll the cannon E is placed, mounted on a carriage, a pile of balls b being on the ground below the muzzle.

The flags B' are attached to staffs c c, and the flags are represented at their lower parts towards the opening A.

The design, it will be seen, is a purely military and national one. It is chiefly designed for likenesses of military men.

Having thus described my design, I claim as new, and desire to secure by Letters Patent—

The general configuration of the parts herein shown and described, to form a new and original design for a mat for Daguerreotype and similar cases.

H. W. HAYDEN.
